(57) **CLAIM**

The ornamental design for a cigarette paper, as shown and described.

DESCRIPTION

The patent or application file contains at least one drawing executed in color. Copies of this patent or patent application publication with color drawing(s) will be provided by the Office upon request and payment of the necessary fee.

1. Cigarette paper

The ornamental design for cigarette paper is shown in figures, which show: figure 1.1: a plan view of the cigarette paper; figure 1.2: a plan view of the cigarette paper being folded; figure 1.3: a side view of the folded cigarette paper.
